International Search Report and Written Opinion, dated Oct. 5, 2020, received in International Application No. PCT/US20/41283. U.S. Appl. No. 16/582,876, filed Sep. 25, 2019.

Primary Examiner — Andrew Kerr(74) *Attorney, Agent, or Firm* — George C. Rondeau, Jr.; Davis Wright Tremaine, LLP(57) **CLAIM**

The ornamental design for a beverage filter, as shown and described.

DESCRIPTION

FIG. 1 is a top perspective view of a beverage filter, showing my new design;

FIG. 2 is a bottom perspective view thereof;

FIG. 3 is a left side elevational view thereof;

FIG. 4 is a front elevational view thereof;

FIG. 5 is a right side elevational view thereof;

FIG. 6 is a rear elevational view thereof;

FIG. 7 is a top plan view thereof; and,

FIG. 8 is a bottom plan view thereof.

The broken lines depict portions of the beverage filter that form no part of the claimed design.

1 Claim, 8 Drawing Sheets(56)
